EXPANSIBLE CHAIN FOR A BRACELET
OR THE LIKE

William C. Boots, Rumford, R. I., assignor to
Foster Metal Products Incorporated, Attleboro,
Mass., a corporation of Massachusetts

Application December 6, 1951, Serial No. 17,637

Term of patent 14 years

(Cl. D45—4)

To all whom it may concern:

Be it known that I, William C. Boots, a citizen of the United States, residing at Rumford, in the county of Providence and State of Rhode Island, have invented a new, original, and ornamental Design for an Expansible Chain for a Bracelet or the like, of which the following is a specification, reference being had to the accompanying drawing forming a part thereof, in which:

Fig. 1 is a plan view of a portion of an expansible chain for a bracelet or the like showing my new design,

Fig. 2 is a plan view thereof showing the chain in expanded condition, and

Fig. 3 is a side elevational view of the chain as shown in Fig. 2.

I claim:

The ornamental design for an expansible chain for a bracelet or the like, substantially as shown.

WILLIAM C. BOOTS.
